VALVE BAG CLOSURE MEANS

Merwin Frankel, Scarsdale, N.Y., assignor to Geigy Chemical Corporation, Greenburgh, N.Y., a corporation of Delaware

Filed Jan. 16, 1963, Ser. No. 251,926
2 Claims. (Cl. 229—62.5)

The present invention relates to valve bags, and more particularly to closure means for valve bags which comprises a bendable transversely extending metal strip secured to the edge of the valve opening which is adapted to be bent around the edges of the valve when the valve has been folded over to close it.

So-called valve bags are multi-ply paper bags which are sealed at both ends, for example by being folded over and sealed or by being sewn, but which have a filling valve therein in the form of a tube which extends through the top of the bag under the folded over or sewn end and through which the material forming the contents of the bag is inserted into the bag.

The industry has long recognized that there is a problem in folding these tubes up and tucking them under the top of the bag after filling of the bag has been completed so that the contents of the bag will not leak out through the tube. After the bags has been filled, and thereafter has been upended during stacking the contents of the bag press against the top of the bag and hold the folded under tube in the folded condition. However, after the bag has been further handled and transported, the contents tend to settle, the pressure on the folded under tube is lessened, and the tube often comes unfolded unless it has been carefully and properly folded under and tucked in the first place.

Moreover, since the tubes are folded and tucked under by hand, the human element enters the picture, with the inevitable result that the tubes are not uniformly folded and tucked, and with the result that occasional human lapses into carelessness produce poorly folded and tucked or incompletely folded and tucked tubes. Consequently, there can be exercised little or no quality control in the closing of this type of bag.

A further problem has been the spilling of small amounts of material which are often left in the tubes themselves at the end of the filling operation. It is difficult to fold the tubes so that such material will not eventually be shaken out of the tube during handling and transportation. Where the contents of the bags are harmless, such as sugar, flour, seed, or the like, such leakage presents only minor problems. Even where the material is likely to be corrosive, such as lime, the problem is a relatively minor one.

However, problems of leakage, both of the material left in the tube during filling and material which leaks out of the interior of the bag after it has been filled, become especially acute when such bags are used for poisonous materials in dry form. In the light of the increasing demand for insecticides, herbicides, pesticides etc. in dry form so that they can be easily spread or dispersed, it has become increasingly important to provide bags from which none of the contents will escape, since the materials are often extremely toxic and the escape of even small amounts could be dangerous.

It is therefore an object of the present invention to provide a valve bag closure which closes the valve tube of the bag securely so that no material can escape from the tube or the bag, and which helps keep the tube from becoming untucked when the bag is handled.

It is a further object of the invention to provide a valve bag closure which closes the valve tube in such a manner that the proper folding of the valve tube is facilitated.

It is a still further object of the invention to provide a

2

valve bag closure which in addition to closing the valve tube of the bag securely and facilitating the closure of the tube and preventing the valve tube from becoming untucked, also makes it easier to tuck the folded tube under the top of the bag and makes it more difficult to fold the tube and tuck it under imperfectly than to fold and tuck it imperfectly.

Another object of the invention is to provide a valve bag closure which will permit the valve tube to be unfolded to check the correctness of the fold and the seal, yet which will not have the closure itself disturbed by this inspection, and which allows the tube to be refolded in the same way as originally folded, if such folding is correct, or refolded correctly if the original folding is improper, also without disturbing the closure, thereby permitting close and rigid quality control of the closed bags.

Other and further objects of the present invention will become apparent from the following specification and claims, taken together with the accompanying drawing, in which:

FIG. 1 is a perspective view of a valve bag with a closure means according to the present invention;

FIG. 2a is a plan view on an enlarged scale of the valve tube of the valve bag of FIG. 1;

FIG. 2b is a sectional view taken on line 2b—2b of FIG. 2a;

FIGS. 3—6 are perspective views similar to FIG. 1 showing the steps of folding and tucking the valve tube of the valve bag of FIG. 1;

FIG. 7 is a view similar to FIG. 2b of a modified form of the tube and bendable strip;

FIGS. 8—10 are views of modified forms of the bendable strip;

FIG. 11 is a perspective view of a different type of valve bag from the valve bag shown in FIG. 1 with a closure means according to the present invention; and

FIGS. 12—15 are perspective views similar to FIG. 11 showing the steps of folding and tucking the valve tube of the valve bag of FIG. 11.

As seen in FIG. 1, a multi-ply paper bag has inward folds 11 in the top portion of the narrow end panels, and the top portions of the side panels have been folded over the inwardly folded narrow end panels to form an inner top panel 12 and an outer top panel 13 which are glued or otherwise secured firmly to the inwardly folded narrow end panels to form the top of the bag 10 and so as to leave a pocket between the top of one end panel and the top panels.

Extending beneath the edges of the panels 12 and 13 and into the interior of the bag is a flattenable tube 14 of paper or the like, which tube preferably projects beyond one of the narrow end panels of the bag. In order to fill the bag, a spout or the like is inserted into this tube and the material is poured through the spout and the tube 14 into the bag.

In a preferred embodiment, the flattenable tube 14, as more clearly seen in FIGS. 2a and 2b, has an upper wall 14a and a lower wall 14b joined to each other at the longitudinal edges thereof to enclose the space within the tube. The end of the lower wall 14b has an extension 15 thereon in which is enclosed a strip 15a of soft bendable material which will remain in the bent condition after it has been bent. Soft metal is quite suitable for this strip 15a. The ends 15b of the strip 15a extend beyond the longitudinal edges of the tube 14 and beyond the sides of the bag 10, and the width of the lower wall 14b which encloses the strip 15a is increased at this point to cover the entire length of the strip 15a.

To close the bag, after the filling spout has been withdrawn from the tube, the tube is flattened and the strip 15a is bent upwardly and back over the flattened tube at least once, and when it is folded only once the fold takes

place along the fold line 16 running along the end of the tube between the tube and the strip 15a, as shown in FIG. 3. The tube is then folded upwardly and back over against itself along the fold line 17 spaced inwardly from the end of the tube, as seen in FIG. 4. At this point the strip will lie against the top wall 14a of the tube with the ends 15b of the strip extending out over the edges of the tube. The ends 15b of the strip are then bent downwardly and under the tube and pressed against the bottom wall 14b of the tube, as shown in FIG. 5.

It will be seen at this point that when the strip 15a is first folded over against the top wall of the tube, this closes the end of the tube so that any material left in the tube when the filling spout is withdrawn must pass at least one fold before it can leak out of the tube. After the fold along the line 17, there are at least two folds which the material within the bag must pass before it can leak out. When the ends 15b are bent around the edges of the tube, this insures that the two folds are held during any further folding or other manipulating of the tube. In addition, it will be seen that by bending the ends 15b around the tube at a point spaced inwardly from the end thereof, a substantially rigid member, at least a member more rigid than the paper tube, is positioned across the tube substantially midway of its length from the point where it goes under the flaps 12 and 13 to the outer end thereof. This helps insure that the tube will stay flat during further folding and tucking, and thus helps preclude the formation of wrinkles in the tube through which material may leak out of the bag.

The final step in closing the tube is to fold the free end of the partially folded tube at least once, and where only one further fold is used, it takes place downwardly and under about a fold line 18 which preferably lies adjacent the bases of the flaps 12 and 13. In folding the free end of the tube under, it will be tucked between the inwardly folded portion of the narrow end panel and the end of the tube extending into the bag, where it will be held by the pressure of the contents of the bag against the top of the bag. The ends 15b of the strip will be out of sight when the tuck is thus properly made.

At this point, it will be observed that material within the bag must pass at least three tight folds in order to leak out, the folds along lines 16 and 17 which are held by the bent over ends 15b of the strip 15a, and the fold along line 18 which is held by the tucked end itself being held under the top of the bag. It is therefore virtually impossible for the material in the bag to leak out.

The ends of the strip 15a serve a double purpose in the present invention, that of securely sealing the tube when they are properly bent around the tube, and that of obstructing tucking of the tube when they are improperly bent around the tube. The former purpose will be appreciated from what has already been described. The latter purpose will be appreciated when it is considered that because the ends 15b extend beyond the side panels of the bag, it will be difficult, although not impossible, to force the end of the tube under the panels 12 and 13 when the ends 15b are not bent around the tube at all, or if only one of them is bent around the tube, so that the tube can be tucked under only with more difficulty than if the ends 15b are properly bent. Even if both ends 15b are only partially bent around the tube, but are not pressed against the wall of the tube, they will stand away from the tube, and the tube still cannot be tucked under easily. Thus, when the strip 15a is properly bent over, both the folds and the tuck can easily be properly made.

Further, a visual inspection in which the tube is unfolded will quickly show whether the tuck is properly made, will also serve to indicate that the fold and bending of the ends 15b is proper, although the fold of the strip 15 and the bent ends need not be disturbed. On the other hand, if a casual visual inspection shows one or both ends 15b to be visible before the tube is untucked, it will be

clear that not only has the tuck not been properly made, but the folding of the tube has likewise not been properly carried out.

The strip 15a, which has been shown as being on the lower wall 14b can of course be secured in like manner to the top wall 14a, in which case the first fold along the line 16 and the second fold along line 17 will be more easily made in a downward direction. However, the two folds will still be present in the tube, and the advantages of the structure as set forth above will be the same.

Likewise, other ways of securing the strip 15a to the tube will suggest themselves to those skilled in the art. For example, the strip 15a could be wrapped in a separate piece of material and a flap of this material glued or otherwise secured to the material of the tube. The strip 15a could be glued directly to an extension of one wall of the tube, as shown in FIG. 8. Alternately it could be stapled to an extension of one wall of the tube by staples 19, as shown in FIG. 9.

20 The material in which the strip 15a is wrapped need not be the same as that of the tube. It could be wrapped in paper, plastic, a women fabric or other suitable material.

Likewise, while the flat shape of the flexible strip 15a is the preferred form, it could have other shapes. For example, it could be a bendable wire having a round cross section, as shown in FIG. 10 at 20.

The strip can also be secured to the outside of the end of the tube 14 with the edge of the strip along the end 30 of the tube, as seen in FIG. 7. The wrapping 15' for the strip 15a' is secured to the outside of the lower tube wall. However, it will also be appreciated that the material of the wall could also serve as the wrapping by being bent downwardly and rearwardly from the end of the tube or being a multiple wall. The manner of folding and tucking the tube is the same with the modified structure of FIG. 7 as with the embodiment of the other figures, except that the first fold of the strip over the end of the tube also folds a length of the tube equal to the width of the strip.

In the embodiment as described above, the valve bag has a top which is folded over and glued, and the tube projects from beneath the folded over top. The invention is also applicable to the so-called sewn bags in which the tops of the side and end panels are merely brought together and a stitching placed along the tops thereof. Such a bag with a valve tube and a closure according to the present invention is shown in FIGS. 11-15.

50 As seen in FIG. 11, one of the narrow side walls 23 is folded inwardly and downwardly along one top corner 25 to leave an outwardly projecting fold 24. The front and rear walls 21 and 22 are sewn together at 27 along the top thereof and a reinforcing strip 26 is placed over the stitching, or the stitching may be over the reinforcing strip. A flattenable tube 28 extends into the bag through the inwardly folded corner and is secured to the inner edges of the fold in a manner not shown so as to seal the inner end of the tube to the bag. The stitching 27 and reinforcing strip may, for convenience in the manufacture of the bag, extend along the top edge of the tube 28.

On one outside face of the tube 28 at the end thereof is secured a bendable strip of material 29 with the ends thereof projecting beyond the edges of the tube 28, in the manner in which the strip 15a is positioned relative to the tube in the embodiment of FIGS. 1-6 and FIG. 7. The strip 29 may also be in the form shown in FIGS. 8-10.

The manner of folding the strip 29 over the end of the tube 28 and then folding and tucking the tube 28 is substantially the same as for the embodiment of FIGS. 1-6, except that since the tube is in the vertical position when it is folded flat, the folds are performed about vertical lines. Thus, as seen in FIG. 12 the strip 29 is folded at least once across the open end of the tube 28, and in FIG. 13 the folded over end is again folded. The

next step, as shown in FIG. 14 is to bend the ends of the strip 29 around the edges of the tube 28, and then the final fold or folds are taken, as shown in FIG. 15, to tuck the closed tube into the top of the bag.

Despite the fact that the tube 29 is vertical when it is folded flat, the closure will have all of the advantages which are discussed above with respect to the form shown in FIGS. 1-6.

It is thought that the invention and its advantages will be understood from the foregoing description and it is apparent that various changes may be made in the form construction and arrangement of the parts without departing from the spirit and scope of the invention or sacrificing its material advantages, the forms hereinbefore described and illustrated in the drawings being merely preferred embodiments thereof.

I claim:

1. In combination, a bag having side and end panels with the side panels brought together at the top, stitching along the top of the bag for securing the side panels together, a flattenable tuck valve tube extending out of one of the end panels of the bag adjacent to the top of the bag and having the upper edge of the flattenable tube sewn to the side panels by the said stitching, the inner end of the tube being secured to said end panel from which it projects, a strip of soft bendable material which will remain in the bent condition after it has been bent secured to the outer end of said tube and extending transversely of the end of the tube with one edge extending along the end of the tube, said strip extending beyond the longitudinal edges of the tube, whereby when the strip is folded over the end of the tube and back against the tube for flattening the tube and the tube is folded back against itself at least once for closing the bag, the ends of the bendable strip must be bent around the edges of the flattened tube for holding the folded over end against the tube before the folded tube can be tucked into the bag so that a secure closure of the tube is insured when the folded tube is tucked into the bag.

2. In combination, a bag having side and end panels, and having top panels at the upper ends of said side

40 GEORGE O. RALSTON, Primary Examiner.

panels folded over on each other and secured to each other, said side panels, top panels and one end panel defining a pocket at the top of said one end panel, a flattenable tuck valve tube extending out of the bag from beneath the folded over top panels and through said pocket, the lateral dimension of the tube in the flattened condition being substantially equal to the spacing of said tops of said side panels when the bag is in the filled condition, a strip of soft bendable material which will remain in the bent condition after it has been bent secured to the outer end of said tube and extending transversely of the end of the tube with one edge extending along the end of the tube, said strip extending beyond the longitudinal edges of the tube and beyond the spaced side panels of the bag at the top of the bag when the bag is in the filled condition and the strip is in the unbent condition, whereby when the strip is folded over the end of the tube and back against the tube for flattening the tube and the tube is folded back against itself at least once for closing the bag, the ends of the bendable strip must be bent around the edges of the flattened tube for holding the folded over end against the tube before the folded tube can be tucked into the pocket so that a secure closure of the tube is insured when the folded tube is tucked into the pocket.
